UNITED STATES PATENT OFFICE.

DONALD SHIELDS ANDREWS, OF CLEVELAND, OHIO, ASSIGNOR TO ANDREWS CRANE CORPORATION, OF CLEVELAND, OHIO, A CORPORATION OF DELAWARE.

HOISTING AND CONVEYING DEVICE.

Application filed December 5, 1921. Serial No. 519,823.

To all whom it may concern:

Be it known that I, DONALD S. ANDREWS, a citizen of the United States, resident of Cleveland, county of Cuyahoga, and State 5 of Ohio, have invented new and useful Improvements in Hoisting and Conveying Devices, of which the following is a specification, the principle of the invention being herein explained and the best mode in which 10 I have contemplated applying that principle, so as to distinguish it from other inventions.

This invention relates to hoisting and conveying devices, particularly to the type in 15 which a rotary boom is suspended from an overhead tractor carriage by means of a depending mast.

The objects of the present invention are to simplify the construction of the supporting 20 carriage and to equalize the load thereon to maintain a substantially equal load on each of the traction wheels.

The annexed drawings and following description set forth in detail the preferred 25 form of my invention and one modification thereof, these, however, constituting but one of the various mechanical forms in which the principle of the invention may be employed.

30 In said annexed drawings:

Fig. 1 is a top plan view of the crane supporting carriage, with the I beam rails cut away to show the wheels of the carriage.

Fig. 2 is a side elevation of the carriage.

35 Fig. 3 is a section on line III—III of Fig. 2.

Fig. 4 is a section on line IV—IV of Fig. 2.

Fig. 5 is a section on line V—V of Fig. 3.

40 Figs. 6 and 7 show a top plan view and a side elevation, respectively, of the entire crane.

Fig. 8 is a top plan view of a modified form of the invention.

45 Fig. 9 is a longitudinal section on line IX—IX of Fig. 8.

Fig. 10 is a transverse section on line X—X of Fig. 9.

50 Figs. 11 and 12 are diagrammatic views illustrating the principle of the invention.

Referring to the drawings, the numeral 1 designates the supporting carriage which runs on I beam rails 2. The carriage 1 com-

prises a body member 3 having bearing members 4 at the ends thereof adapted to receive the suspension bolts 5 of the front and rear trucks. The bolts 5 are fixed to the truck frames and are threaded at their lower ends to receive the nuts 6 to support the body member 3.

The front and rear trucks are exactly alike and interchangeable. A description of one, therefore, will suffice for both. The truck consists of a rigid rectangular channel iron frame 7 carrying a pair of axles 8 and 9 to which are fixed the flanged wheels 10 which travel on the track rails 2. The frame 7 is provided with a pair of intermediate cross bars 11 which carry the block 12 in which the suspension bolt 5 is fixed. Extending from one of the bars 11 to the end of the frame 7 are a pair of longitudinal bars 13 from which is suspended the driving motor 14. The shaft of the motor 14 carries a small pinion 15 meshing with a larger pinion 16 fixed to a countershaft 17 carried between one of the bars 13 and the side rail of the frame 7. The countershaft has fixed thereto a second pinion 18 meshing with a pinion 19 fixed to the axle 9.

The swivel connections between the trucks and body member 3 of the carriage permit the carriage to readily pass over sharp curves in the track, the body member 3 of the carriage being relatively narrow so as to remain clear of the rails 2 in passing such curves.

The depending boom supporting mast 20 is suspended from and fixedly secured to the carriage 1 by means of a suspension frame 21. The suspension frame 21 has vertical posts 22 on opposite sides of the body member 3 of the carriage. The posts 22 carry between them a rectangular casting 23 having a convex under surface fitting in a concave socket 24 in the upper face of the body member 3 at the center thereof forming a universal joint between the mast and the carriage, whereby said mast may swing in any direction, such swinging movement, however, being limited as will be hereinafter described. The suspension frame 21 has longitudinal channel iron side rails 25 carrying cross bars 26 fixed to their upper flanges at the front and rear thereof. The cross bars 26 carry on their upper

faces angle guide brackets 27 engageable with opposite sides of the bearing members 4 on the front and rear trucks, by means of which the suspension frame 21 is maintained in alinement with the body member 3 of the carriage. The cross bars are positioned directly beneath the suspension bearings of the front and rear trucks which is centrally positioned with respect to the front and rear wheels 10 of each truck. The outer ends of the cross bars 26 carry rollers 28 mounted in bearing members 29 upon the upper faces of the bars 26 and engageable with the underside of the rails 2. These rollers may hence be properly considered a part of the arms and constitute means for reducing the friction between said arms and the underside of said rails 2. The said rollers 28 are somewhat wider than the rails 2 to maintain engagement with same in passing around curves.

The mast 20 has a cylindrical casing 30 rotatably mounted thereon. The upper end of the said casing 30 has fixed thereto a gear 31 meshing with a pinion 32 which is driven from a motor 33 carried by the frame 21 through suitable reduction gearing. The said casing 30 furthermore carries a sleeve 34, Fig. 1, mounted for rotation therewith and vertical adjustment thereon. The sleeve 34 carries a boom 35, operating mechanism 36 for the hoisting cable 37 and a mechanism 38 for adjusting the sleeve vertically along the mast. The boom 35 carries an operator's cab 39 from which all the crane operating motors are controlled, as well understood in the art. The specific crane herein shown is in itself not a part of the present invention. The crane herein shown being substantially the same as that shown and described in my Patent No. 1,367,907 issued February 8, 1921.

In Figs. 8, 9 and 10 I have shown a modified form of my invention. In this modification the carriage 40 is exactly the same as the carriage 1 in the preferred form except that the body member 41 is provided with a rectangular mast receiving socket 42 adapted to receive the upper end of the depending mast 43 which is supported upon a pivot pin 44 the axis of which is disposed longitudinally with respect to the carriage. The socket 42 is enlarged to permit a slight pivotal movement of the mast therein. Just below the carriage a cross member 45 is rigidly secured to the mast 43. The outer ends of the cross member 45 carry wide rollers 46 engageable with the under faces of the rails 2. There is preferably slight amount of play between the rollers 46 and the tracks 2, so that pressure is exerted upon the rollers 46 only when the load on the mast tends to swing the mast to one side or the other or where there is an irregularity in the level of the track rails. The rollers

46 are somewhat wider than the rails 2 to allow for lateral play and to prevent disengagement thereof in passing around curves.

Below the cross member 45 the mast 43 is provided with a rotatable sleeve 47 which carries a vertically adjustable slide and boom such as shown in Figs. 6 and 7. Rigidly suspended from the cross member 45 is a platform 48 supporting a motor 49 adapted to rotate the sleeve through suitable gearing.

Figs. 11 and 12 illustrate diagrammatically the principle of the invention. If the mast 20 were suspended by a universal joint from the central portion of the body member 3 without the material limitation of movement which is provided in the illustrated structure, so as to be free to assume its natural position when a load is applied to the end of the boom 35, the weight would always be equally distributed between the front and rear trucks and between the wheels 10 on opposite sides of the carriage. Such a construction is, however, obviously undesirable. On the other hand, if the mast 20 is rigidly connected to the carriage, the component of the load tending to move the mast out of vertical position causes an unequal distribution of the load on the traction wheels of the carriage. If the boom is extending laterally the traction wheels on the rail away from the boom tend to lift off the rails and consequently are likely to slip. If the boom is extending forwardly the rear wheels tend to raise off the rails. The purpose of the present invention is to retain the necessary rigidity in the mast and at the same time to maintain equal traction on the wheels of the carriage. This is accomplished by providing the arms 25 rigidly connected to the pivoted mast and carrying the rollers 28 engageable with the under side of the rails beneath the trucks. When a load is applied to the boom 35 when the boom is extending forwardly the mast 20 swings slightly to the rear and the rear rollers 28 engage the rails beneath the rear truck of the carriage transmitting the rearward thrust on the mast 20 to the rear rollers 28 and rails 2 instead of to the carriage and maintaining an equal load on the rear traction wheels. If the boom is extending laterally when the load is applied the rollers 28 on the side opposite the boom are brought into engagement with the rails and receive the thrust on the mast 20 due to such load, maintaining an equal load on the traction wheels at opposite sides of the carriage.

In the modification shown in Figs. 8, 9 and 10 the boom is mounted to swing in a lateral direction only and the arm 45 with its rollers 46 prevents lateral tilting of the carriage only. Since the tendency to tilt is greater in a lateral direction due to

greater leverage, the simpler form shown in Figs. 8, 9 and 10 may be preferable in some cases.

What I claim is:

- 5 1. In a hoisting and conveying device, the combination of a track comprising spaced rails; a carriage mounted to travel along said track; a boom supporting mast pivotally suspended from said carriage for swinging movement with respect thereto; and means carried by said mast and engageable with said rails to limit the oscillatory movement of said mast.
- 10 2. In a hoisting and conveying device, the combination of a track comprising a pair of spaced rails; a carriage having wheels running on said rails; a boom supporting mast pivoted to said carriage between said rails for swinging movement with respect to said carriage and arms rigidly connected to said mast and engageable with the under side of said rails to limit the oscillatory movement of said mast.
- 15 3. In a hoisting and conveying device; the combination of a track comprising a pair of spaced rails; a carriage comprising front and rear trucks having wheels running on said tracks and a body member having swiveled connection with said trucks; means for driving said wheels; a boom supporting mast pivotally suspended from said body member; and arms rigidly connected to said mast and engageable with the under side of said
- 20 30 35 rails to limit the oscillatory movement of said mast.

4. In a hoisting and conveying device, the combination of an overhead track; a carriage having spaced traction wheels traveling on said track; a boom supporting mast pivotally suspended from said carriage between said traction wheels; and means carried by said mast and engageable with said track to limit the swinging movement of said mast and to equalize the load on said traction wheels.

45 5. In a hoisting and conveying device, the combination of an overhead track comprising spaced rails; a carriage comprising front and rear traction wheels; and a body member connecting said trucks; a boom supporting mast suspended by a universal joint from said body member; and means for limiting the swinging movement of said mast in any direction and for equalizing the load on said traction wheels.

50 55 6. In a hoisting and conveying device, the combination of an overhead track comprising spaced rails; a carriage comprising front and rear trucks having traction wheels, and a body member connecting said trucks; a boom supporting mast suspended by a universal joint from said body member; and an arm rigidly carried by said mast, said arm carrying rollers engageable with the under sides of said rails beneath said front and rear trucks.

Signed by me this 11th day of November, 1921.

DONALD SHIELDS ANDREWS.
